Primary Examiner — Ralf Seifert(74) *Attorney, Agent, or Firm* — GE Global Patent Operation; John A. Kramer(57) **CLAIM**

The ornamental design for a fuel pump mounting structure, as shown and described.

DESCRIPTION

FIG. 1 is a first perspective view of an ornamental design for a fuel pump mounting structure, according to the invention. FIG. 2 is a front view of a fuel pump mounting structure of FIG. 1.

FIG. 3 is a back view of a fuel pump mounting structure of FIG. 1.

FIG. 4 is a left view of a fuel pump mounting structure of FIG. 1.

FIG. 5 is a right view of a fuel pump mounting structure of FIG. 1.

FIG. 6 is a top view of a fuel pump mounting structure of FIG. 1; and,

FIG. 7 is a bottom view of a fuel pump mounting structure of FIG. 1.

The shading and contour lines in FIGS. 1-7 are for illustrative purposes only and form no part of the claimed design.
